Primary Examiner — Angela J Lee(74) *Attorney, Agent, or Firm* — LegalForce RAPC Worldwide(57) **CLAIM**

The ornamental design for a mini PC station, as shown and described.

DESCRIPTION

FIG. 1 is a front top right side perspective view for a mini PC station, showing my new design;

FIG. 2 is a front elevational view of FIG. 1 thereof;

FIG. 3 is a rear elevational view of FIG. 1 thereof;

FIG. 4 is a left side elevational view of FIG. 1 thereof, the right side elevational view being a mirror image.

FIG. 5 is a top plan view of FIG. 1 thereof;

FIG. 6 is a bottom plan view of FIG. 1 thereof; and,

FIG. 7 is an exploded front top right side perspective view of mini PC station of FIG. 1 thereof.

The broken lines indicate unclaimed portions of the design and form no part of the claimed design.

1 Claim, 7 Drawing Sheets(56)
